(57) **CLAIM**

The ornamental design for a tire, as shown and described.

DESCRIPTION

FIG. 1 is a front perspective view of a tire showing the new design;

FIG. 2 is a front view thereof;

FIG. 3 is a left side view thereof;

FIG. 4 is a right side view thereof;

FIG. 5 is a partial sectional view along line 5-5 in FIG. 2; and,

FIG. 6 is a partial sectional view at line 6-6 in FIG. 2. In the drawings the portions of the article shown in broken lines form no part of the claimed design.
